UNITED STATES PATENT OFFICE.

ROBERT SAMUEL KIRKPATRICK, OF HARLAN, IOWA, ASSIGNOR OF ONE-FOURTH TO R. P. DAMMAND, OF SAME PLACE.

PORTABLE ELEVATOR AND WAGON-UNLOADER.

SPECIFICATION forming part of Letters Patent No. 449,447, dated March 31, 1891.

Application filed May 12, 1890. Serial No. 351,519. (No model.)

To all whom it may concern:

Be it known that I, ROBERT SAMUEL KIRKPATRICK, a citizen of the United States, residing at Harlan, in the county of Shelby and

5 State of Iowa, have invented certain new and useful Improvements in a Portable Elevator and Wagon-Unloading Device, of which the following is a specification.

My invention relates to elevators and wag-
10 on-unloaders designed, within a certain lim-
ited field, to be portable while mounted in con-
dition to use, and within a larger field to be
portable from place to place and readily ar-
ranged in suitable condition for use.

15 The object of my invention is to obtain a
portable elevator and wagon-unloader by
which an ordinary farm-wagon may be ex-
pediently unloaded of wheat, corn, or other
like article contained therein, and such arti-
20 cles may be elevated into a proper receptacle
therefor contiguous to but not a part of my
portable elevator and wagon-unloader by
power derived from the work of the horses,
mounted on a horse-power contained in the
25 wagon-unloader, while yet hitched to the
wagon in which the grain or corn has been
brought to and upon the elevator and wagon-
unloader.

30 A further object of my invention is to con-
struct a portable elevator and wagon-unloader
with the several parts thereof so disposed and
arranged with regard to each other that the
load contained in the wagon may be unloaded
35 therefrom without "hand labor," as it is called;
and, further, after the load or a part thereof
has been unloaded from the wagon it may be
elevated into a receptacle provided therefor
by the horses attached to the wagon, and
40 without unhitching the horses from the wagon.

45 A further object of my invention is to ob-
tain a portable elevator and wagon-unloader,
by the use of which an ordinary farm-wagon
may be unloaded and the contents elevated
into the receptacle provided therefor without
50 backing or turning the team or the wagon to
which such team is attached in entering upon
or departing from the device by which such
wagon is unloaded, and its contents elevated,
as stated.

55 A still further object of my invention is to
provide a portable elevator and wagon-un-

loader upon and about which horses used to
farm-work only may be safely handled and
employed.

The manner in which I attain the several 55
objects sought by me is set out and described
and claimed in this specification, and illus-
trated in the drawings attached hereto and
forming part hereof, in which—

Figure 1 is a side elevation of my portable 60
grain-elevator and wagon-unloader in position
for the driving thereon of a team and loaded
wagon, to which such team is hitched; Fig. 2,
a top plan view thereof; Fig. 3, a bottom plan
view thereof; Fig. 4, a sectional view on line 65
4 4 of Fig. 2; Fig. 5, a longitudinal sectional
view of the horse-power forming an element
in my invention, by which the elevating mech-
anism of the device is actuated; Fig. 6, a hori-
zontal longitudinal section of the horse-power; 70
Fig. 7, a side elevation of the lifting-aprons
of the elevator and the mechanism actuating
the lifting-aprons; Fig. 8, a side elevation of
the platform and approaches thereto and a
modification of the mechanism controlling the 75
position of such approaches; Fig. 9, a detail
of the mechanism controlling the position of
the upper part of the frame of the elevating-
aprons; Fig. 10, an end elevation of the ele-
vating-aprons with horizontal aprons and a 80
blowing-fan for separating shelled corn and
other material from corn on the ear and for
cleaning such shelled corn of foreign mate-
rial, and Fig. 11 a transverse section of a
corn-crib and my device therein in position 85
for use in connection therewith.

Similar letters of reference indicate the same
parts in the several figures of the drawings.

A is a platform mounted on wheels *a a*. A
loaded wagon can be driven on platform A. 90

A' is an approach pivoted to platform A
and adapted to turn upon its pivot, so that
the outer end thereof may rest upon the ground
or be raised therefrom. When the outer end
of approach A' rests upon the ground, the ap- 95
proach forms a roadway, over which a team
and wagon can pass to mount upon the plat-
form A.

A² is a platform pivoted at the other end
of platform A and forms an exit from such 100
platform A. The platform A is of such length,
as compared with an ordinary farm-wagon,

that when a farm-wagon is located upon the platform in suitable position to be unloaded the team, hitched to the wagon and consisting of not more than two horses, stands upon the 5 exit A². When the wagon is unloaded and the team with the wagon is to be driven from the platform A, the exit A² is turned from the position illustrated in Fig. 1 of the drawings upon the hinges X X, (shown in section in 10 Fig. 4,) attaching it to the platform A, so that the free and outer end of this exit will rest upon the ground when the horses are driven down such exit A² with the empty wagon attached to them.

15 A³ are posts pivoted to platform A on pivots A⁴. There are four of these posts—one at each corner of the platform A. The two of the posts A³ on the right-hand side of the platform A are tied together by tension-rod 20 A⁵, while the two upon the left-hand side of the platform are tied together by a like tension-rod, also lettered A⁵.

A⁶ A⁶ are chains extending from the top of the posts A³ to the approach A' and the exit 25 A², respectively. The platform approach A' is of greater weight than the platform exit A² and the permanent load carried thereby, (such permanent load consisting of a tread horse-power hereinafter described,) and hence 30 when the friction-brake with which platform exit A² is provided, and which will also be hereinafter fully described, is released the approach A' and exit A² will, by gravity, assume the position illustrated in Fig. 1 of the 35 drawings. When, however, a team consisting of one or two horses is upon the exit A², the added weight of the exit and the team is greater than is the weight of the approach A', and hence if the friction-brake referred 40 to on exit A² is released exit A² will, by gravity, turn upon its pivot-hinges X X until the free end thereof comes in contact with the ground or other permanent object provided therefor. An inspection of Fig. 1 will show 45 that when the exit A² turns upon its hinge the chain A⁶, attached to such exit A², will necessarily follow the exit and will draw or pull after it the upper end of the post A³, to which such chain is secured, and the post 50 will therefore turn upon its pivot A⁴, and as this post is connected by tie-rods A⁵ to the post A³ at the other end of the platform A, upon the same side of such platform, such other post A³ will also turn upon its pivot, drawing after it the chain A⁶, attached to such second post and to the approach A', and the free or outer end of approach A' will 55 thereby be raised as the free and outer end of the exit A² is lowered. By the mechanism 60 illustrated in Fig. 1 and last above described for controlling the position of the approach A' and exit A² power must be applied directly thereto, as by the weight of a team on exit A² or a lifting of approach A' at the time 65 65 the brake (consisting of the rack a², pinion a³ gearing therewith and secured rigidly on the shaft a⁴, brake-wheel a⁵, also secured rig-

idly to said shaft a⁴, brakes a⁶, controlled by lever a⁷, rod a⁸, and lever a⁹) is released in order to effect a change of the position of the approach and exit from that illustrated in Fig. 1 to one in which a team and wagon can drive from the platform A. To change the position of the approach A' and exit A² from the position illustrated in Fig. 1, when the operator 70 is standing upon the platform A, near to the lever a⁹ and there is no team on platform A, mechanism substantially like that illustrated in Fig. 8 is employed. In this modification posts A⁸ A⁸ are rigidly secured to the platform A and upon the upper ends of such posts are placed idlers Y Y, over which pass the ropes A⁷ to the drum O.

P is a wheel rigidly secured to the shaft p, to which shaft is also rigidly secured the 80 drum O.

P' is a rope or cable passing over wheel P. By pulling upon the rope P' ropes A⁷ A⁷, attached to approach A', may be wound or unwound at will upon drum O, thereby raising 90 or lowering approach A', and ropes A⁷ A⁷, attached to exit A², will be unwound or wound upon this drum O, alternating with the rope secured to approach A'. In this modification a partial counterbalance of the approach and 95 exit is obtained in the same manner as by the device first described, wherein the posts A³ are pivoted. I do not, however, limit myself to either construction, as it is evident that where the approach A' and exit A² are pivoted and made to partially counterbalance each other any suitable mechanism may be 100 employed, and my invention will be thereby substantially made use of.

In order to unload a wagon upon my portable elevator and wagon-unloader, the team hauling the wagon is driven up the approach A' over the platform A and upon the platform A². The wagon hitched to such team will remain upon the platform A. The hook b at 110 the lower end of chain B (see Fig. 1) is then attached to the forward part of the body of the wagon. By pulling upon the rope B² drum B' is actuated through connecting-gear b' b² and the chain B thereby wound upon the 115 drum B', thus elevating the forward part of the body of the wagon. The tail end of the wagon will, when the forward part of the body thereof is elevated as described, be over the trap-door C. Trap-door C is thrown back into 120 the position illustrated in Fig. 2, thereby opening the pit C', into which the grain will fall when the tail-board is removed from the wagon.

C² C² are the inclined bottoms of the pit C' 125 and extend toward the elevating-aprons hereinafter described upon each side of the platform A. The entire load may be thrown to the right or left elevating-aprons, as desired, by changing the position of the movable dividing-board C³. In Fig. 7 of the drawings this dividing-board C³ is placed in position to throw the grain to the elevating-apron upon the right-hand side. When the dividing- 130

board C³ is removed from the pit C', the contents of the pit will extend or fall to both the right and left hand elevating-aprons.

The mechanism actuating the elevating-aprons is extremely simple and consists of the ordinary tread horse-power heretofore employed for divers purposes, but is by me mounted within the platform or exit A² in the following manner.

10 D D are the slats upon which the horses stand.

E is a shaft suitably journaled in approach A².

15 E' are wheels rigidly secured to the shaft. Over these wheels the chains to which the slats D are secured travel.

F is a shaft, also suitably journaled in the platform or exit A².

20 F' are pulleys turning loosely on shaft F.

The chains to which the slats D are attached also travel over these pulleys. By inspection of Figs. 5 and 6 it will be evident that when the slats D are caused to move in the direction indicated by the arrow in Fig. 5 the shaft

25 E will be turned thereby, as will also the loose pulleys F'. I therefore provide the sprocket-wheel E², rigidly secured to shaft E, sprocket-wheel F², rigidly secured to shaft F, and sprocket-chain F³, running over and connect-

30 ing these sprocket-wheels, and thereby revolution in shaft E is transmitted to shaft F.

On the outer end of shaft F, at one end thereof, is rigidly secured sprocket-wheel G, and at the other end thereof is rigidly secured

35 friction brake-wheel G'. Over the sprocket-wheel G there is placed sprocket-chain g, communicating the motion of wheel G to the elevating mechanism by the devices about to be described. The friction-brake, consisting of strap g', extending around brake-wheel G', rod g², and lever g³ controls the rotation of shaft F.

40 H is a shaft journaled to the platform A, having rigidly secured thereon sprocket-wheel

45 H', over which sprocket-chain g turns. H² is a gear-wheel also rigidly secured on shaft H and intermeshing with gear-wheel I', rigidly secured on shaft I. i is a fly-wheel rigidly secured to shaft I. I² is a beveled gear-wheel, 50 also rigidly secured to shaft I and intermeshing with beveled gear-wheel J' on shaft J.

J² is a sprocket-wheel rigidly secured to shaft J.

K is a journaled shaft having rigidly secured thereon sprocket-wheel K' and geared wheel k.

K² is a sprocket-chain turning over wheel K' and wheel J².

55 L is a journaled shaft having rigidly secured thereon geared wheel l and sprocket-wheel L', and L² is a sprocket-chain passing over sprocket-wheel L' and also over sprocket-wheel L³ at the top of the elevating-apron frame.

60 K⁴ is a sprocket-chain passing over sprocket-wheel K³ on shaft K and sprocket-wheel L⁴ at the top of the other elevating-apron frame.

M M are shafts journaled at the upper ends of the elevating-aprons in frame N.

M' are sprocket-wheels over which the elevating-apron chains M² turn.

m m are elevator-buckets, and m' m' are wire fingers or forks secured to the elevating-chain M² and adapted to engage with large articles—as with corn on the ear—in the pit C' and elevate the same over sprocket-wheels at the top of the apron when the machine is in operation and discharge them into a suitable receptacle through the spout attached to the top of the elevating-apron frame N.

An inspection of the several shafts H, I, J, L, K, and M, with the several gear and sprocket wheels rigidly secured thereon, respectively, will show that these several shafts and wheels are arranged, connected, and intermeshed for the sole purpose of transmitting motion from the shaft F of the horse-power in the exit A² to the elevating-aprons M² M³, and no particular invention is claimed by me in this arrangement of the transmitting mechanism, and such mechanism may be varied in formed at the will of the person constructing the device.

In order to move my portable elevator and wagon-unloader from one grain or corn receptacle to another receptacle in the same yard, it is at times necessary to draw the upper end of the elevating-apron frames and the journaled shafts M M, carried thereby, in over the platform A, and for this purpose I have provided the joint n in the frame N and have provided the cross-arms N' N², pivoted, respectively, to frame N at n' and n². N³ is a pulley turning loosely on a shaft in one of these arms, and N⁴ is a cord secured to the other of the arms and running over the pulley N³. By pulling one or the other end of the cord N⁴ arms N' N² may be brought into the position illustrated in Fig. 7 or into the position illustrated in Fig. 9, as desired.

Q is a link jointed at q to platform A and at the other end thereof united by joint q' to the link Q'. In order to trig the wheels of the wagon on the platform A in position so it will not move backward when the upper end of the body thereof is elevated, these links Q' are brought upward into the position illustrated in Figs. 1 and 8, when the wheel Q², being one of the hind wheels of the wagon, is in front of the link Q.

S is a fence around the sides of the exit A², and T is an ordinary hay-crib which may be mounted on gates turning on hinges secured to the upright S' of the side fence S.

U U are cords or ropes, one end of which may be secured to the approach A' and exit A², and the other end, after passing through block u, secured to cleats U' on the framework of the platform A. The purpose of the rope U is to draw the approach A' and exit A², respectively, into an extreme upward position independently of each other when my portable elevator and wagon-unloader is to be moved a considerable distance on the high-

way. When the device is in position for operation, the rope U is unfastened from the approach A' and from the exit A², respectively, and moved out of the way of the team 5 and wagon passing to and from the platform A.

In Fig. 10 there is illustrated in section two horizontal aprons. Apron V is moved in the direction of the arrow thereover by mechanism connecting the apron with the tread horse-power in the exit A². V' is a like apron, also moved in the direction of the arrow thereover. V² V² are casings forming pits surrounding the lower end of the elevating-aprons in frame 15 N, and V³ is a slit or opening in the casing V², adapted to allow shelled corn to drop through upon the aprons V V', respectively. W is a fan. W' is a screen. The current of air generated by the fan W is directed through 20 the falling material extending or falling from apron V to the apron V', and from the pit V² over apron V', and foreign material, as snow, is thereby separated from the shelled corn. The cleaned corn is then delivered from apron 25 V' into receptacle W². Where corn on the ear is to be elevated into cribs, (as crib W³, Fig. 11,) the elevating-buckets m m are not required upon the elevating-apron, forks m' m' alone being necessary.

30 The manner of operation of my device is: A team drawing a loaded wagon is driven over the approach A', the team taking a position on the horse-power D, and the wagon resting on the platform A. The forward end of the 35 body of the wagon is secured to the hook b, and by pulling on the rope B², as hereinbefore described, the forward part of the body of the wagon is elevated. The trap-door C is removed from well C'. The tail-board is re-

40 moved from the wagon and the load in the wagon allowed to slide into the well or pit C'. At the same time the friction-brake on wheel G', controlled, as hereinbefore described, by lever g³, is released, and the horse- 45 power D thereby released and set in motion by the weight of the horses, in the ordinary manner in which a horse-power is set in motion. The team will thus, necessarily, actuate the horse-power, and, through the transmitting mechanism hereinbefore described, the elevating-buckets m m or the elevating-arms m' m' will elevate the contents of the pit or well C' therefrom over the shaft M at the upper end of the frame N and into the receptacle provided therefor, the frame N at the upper end thereof having a spout projecting into the receptacle into which the load is to be conveyed.

55 Having thus described my invention and its 60 method of operation, what I desire to claim by Letters Patent of the United States is—

1. The portable elevator and wagon-unloader consisting of a platform mounted on wheels, elevating-aprons extending upward from the sides of the platform and adapted to raise grain or corn dumped into a well in the platform, combined with an approach

platform and an exit platform pivoted, respectively, at each end of the mounted platform, such pivoted approach and exit platforms being connected together so that the outer end of one shall be raised when the outer end of the other is lowered and shall partially counterbalance when pivotally mounted, one of such pivoted platforms 70 adapted to form a roadway over which a team and loaded wagon may be driven upon the mounted platform and the other a roadway over which the team and wagon may be driven from the platform, substantially as described.

2. A portable elevator and wagon-unloader consisting of a platform mounted on wheels, elevating-aprons extending upward, one from each side of the platform, and adapted to 85 raise grain dumped into a pit in the platform, combined with pivoted platforms secured to each end of the platform mounted on wheels, a rotatable apron forming a tread in one of the pivoted platforms, such pivoted platforms 90 being connected together so that the outer end of one shall be raised when the outer end of the other is lowered and shall partially counterbalance each other when pivotally moved, and one of such pivotal platforms 95 adapted to form a roadway to mount upon the platform and the other a roadway to depart therefrom, substantially as described.

3. In a portable elevator and wagon-unloader, the combination of a platform mounted 100 on wheels, a well in the platform, the door covering the well forming when placed thereover a portion of the floor of the mounted platform, platforms pivoted to the mounted platform and adapted to have the free ends 105 thereof rest upon the ground, one of such pivoted platforms thereby forming a passage-way to and the other a passage-way from the mounted platform for teams, elevating-apron extending from the bottom of the well to receptacles adapted to be filled by the contents 110 of the wagon driven upon the platform, and such elevating-apron having wires extending outward therefrom forming fingers, and the well having holes in the lower part of the 115 casing thereof adapted to allow shelled corn to pass through, but not adapted to permit larger substances, as corn on the ear, to pass through, substantially as described.

4. A portable elevator and wagon-unloader 120 consisting of a platform mounted on wheels, elevating-aprons extending upward and adapted to raise grain dumped into a pit in the platform, combined with pivoted platforms secured to each end of the mounted 125 platform, a rotatable apron forming a tread in one of the pivoted platforms, such pivoted platforms being connected together so that the outer end of one shall be raised when the outer end of the other is lowered and shall 130 partially counterbalance each other when pivotally moved, an elevating-chain adapted to be secured to the front end of a wagon on the platform, whereby a loaded wagon may be

driven upon the platform, the team being upon the tread formed by the rotatable apron in the elevated pivoted platform forming when lowered an exit from the mounted platform, and the forward end of the wagon raised and the contents thereof dumped into the pit in the platform and raised from such pit by the horses on the tread to receptacles provided for such contents of the wagon, substantially as described.

5. A portable elevator and wagon-unloader consisting of a platform mounted on wheels, elevating-aprons extending upward from the sides of the platform, pivoted platforms secured one to each end of the mounted platform, a rotatable apron forming a tread in one of the pivoted platforms, such pivoted platforms being connected together so that the outer end of one shall be raised when the

outer end of the other is lowered and shall 20 partially counterbalance each other when pivotally moved, the frames in which the elevating-aprons move having a joint therein, the lower portion of such frame being rigidly secured to the mounted platform and the upper portion having an arm extending inward, a loose pulley on one of such arms, and a rope rigidly secured to the other of such arms, one end of such rope passing over the loose pulley in the other arm and from thence to the 25 mounted platform, the other end of the rope extending directly to the mounted platform, substantially as described.

ROBERT SAMUEL KIRKPATRICK.

In presence of—

JOHN T. JACK,
CHARLES FOSS.
